UNITED STATES PATENT OFFICE

2,468,918

TOY RIDING SPUR

Carl E. Bowers, Los Angeles, Calif.

Application February 7, 1947, Serial No. 726,992

1 Claim. (Cl. 54—83)

1

This invention relates to a toy, and particularly pertains to a toy riding spur.

Young children have a desire to play "cowboy," and particularly to wear the usual cowboy paraphernalia. There is a demand therefore for replicas of equipment used by cowboys but which might be used safely by children without harm while giving them the pleasure of wearing equipment which resembles the real articles now in use. This particularly applies to riding spurs, and it is the principal object of the present invention to provide a toy riding spur which may be easily mounted upon the shoe or slipper without marring it, and which will make a noise resembling the clicking of a spur as a person walks.

The present invention contemplates a spur structure which is yieldable and may be easily mounted in an embracing position around the heel of a shoe or slipper, and which is fitted with gripping means tending to hold the spur in position without marring the shoe and without the necessity of positive fastening members, the structure being further provided with a rowel which will make a noise.

The invention is illustrated by way of example in the accompanying drawing in which:

Figure 1 is a view in side elevation showing the spur as applied to a slipper, which is indicated in dotted lines.

Fig. 2 is a view in transverse section through the spur as seen on the line 2—2 of Fig. 1.

Referring more particularly to the drawing, 10 indicates a slipper or shoe upon which a spur 11 is mounted. This spur is formed with a frame structure comprising an inner U-shaped frame member 12 and a pair of complementary outer frame members 13. The U-shaped frame member is formed with relatively straight parallel legs 14 which lie against the inner faces of the outer frame members 13. The outer members 13 have a parallel portion 15 and ogee curve portions 16 terminating in flat parallel portions 17. The flat portions 14 of the U-shaped inner frame member and the flat portions 15 of the outer frame member are fastened together by rivets 18 at a point along the flat portions and are secured together at their ends by rivets 19 which also secure gripping cups 20 in position. The gripping cups 20 are preferably made of

2

rubber and have a cup-shaped inner face 21 which receives a disc 22. The disc 22 lies against the inner face of the cup-shaped portion and may be formed integral with the rivet 19. The cup-shaped portion thus provides an annular gripping edge 23 which may rest against the surface of a shoe or slipper and which will tend to hold the spur in position.

The flat parallel portions 17 of the outer frame member 13 are spaced a distance apart and accommodate a rowel 24. This rowel is in the form of a circular disc. It is made with a central opening 25 through it, which opening accommodates a rivet 26. The rivet 26 extends through perforations 27 in the members 17. Mounted upon the rivet is a spacing sleeve 28 which holds the parallel portions 17 of the frame members 13 in spaced relation to each other. The distance between the opposing faces of the members 17 is greater than the thickness of the rowel, and the diameter of the opening 25 through the rowel is materially greater than the outside diameter of the spacing sleeve 28. Thus, when the person wearing the spur takes a step there is a tendency for the rowel to move with relation to the sleeve 28 and to rattle. It is desirable that the rowel 24 shall be made of some metal which will rattle when it contacts with the members 17 and the sleeve 28. The frame members 12 and 13 are made of spring metal so that the gripping cups 20 may be held yieldably against the surface of the shoe or slipper at the opposite sides of the heel.

When the spurs are to be worn the frame structure 12 is flexed so that the gripping cups 20 are spread apart to permit the inner frame member 12 to assume an embracing position around the heel of the slipper or shoe. After the spur has been placed in position the frame member 12 will tend to hold the cups against the surface of the shoe and maintain the spur in the horizontal position shown in Fig. 1 of the drawing. When the wearer of the spur walks the disc-shaped rowels will rattle and click.

It will thus be seen that the spur structure here disclosed is simple and inexpensive in construction and may be easily mounted upon a shoe without the use of special fastening means, and will produce a rattling noise when the wearer takes a step.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

A toy riding spur comprising a U-shaped frame structure made from a strip of resilient metal bent to dispose the width of the metal at right angles to the plane of the frame, a pair of rubber gripping cups secured in opposing relation to each other on the inner faces of the free ends of said frame member, said cups having a concaved exposed face, a pair of resilient rowel supporting members made of flat strip metal and secured on the outer faces of said U-shaped frame member, the rear ends of said supporting members extending rearwardly from the frame member and lying parallel to each other at opposite

sides of the median line through the U-shaped member, a rivet extending through the parallel portions of said supporting members, and a disc-shaped metal rowel having an opening substantially greater than that of the rivet and being mounted upon the rivet between the parallel portions of the supporting members.

CARL E. BOWERS.
